H. C. FOWLER

EYE PROTECTOR

Filed Aug. 5, 1927

FIG. 1.

FIG. 2.

FIG. 3.

HERBERT C. FOWLER.

By Rindor & Rindor

Attorney

UNITED STATES PATENT OFFICE.

HERBERT C. FOWLER, OF COLUMBUS, OHIO.

EYE PROTECTOR.

Application filed August 5, 1927. Serial No. 210,925.

This invention is a device to protect the eyes of a person who is operating a spray paint gun, and has for its object the provision of a device which may be worn as a pair of 5 goggles and protect the eye from the paint spray while affording a view of the work and which may be easily cleaned during use.

The accompanying drawing illustrates an embodiment of the invention which has been 10 successfully used, and the invention resides in certain novel features which will be herein-after first fully described and then more particularly pointed out in the appended claims

In the drawing:—

15 Fig. 1 is a front elevation of a pair of goggles embodying the invention;

Fig. 2 is an enlarged vertical section of one of the guards;

20 Fig. 3 is an enlarged detail perspective of the vision area of a guard.

In the drawing, the reference numeral 1 indicates the nose bridge of a goggle frame, the frame having hoods 2, temples 3 and lens rings 4 all of well-known or any approved 25 construction.

In the practice of the present invention, there is fitted in each lens frame, in substitution for the usual lens, a disk 5 of some light impervious material, preferably aluminum, 30 having a very narrow cruciform slit 6 at its center, the branches or arms of the slit running vertically and horizontally. The slit may be formed by punching and the walls of the slit are pressed outwardly, as shown 35 at 7, to form ribs whereby the edges of the slit will be offset forwardly from the face of the disk. The back of the disk is preferably black so that the wearer's eye will naturally seek the only source of light available, to wit, 40 the cruciform slits.

When applying paint by the use of a spray gun, the spray of paint spreads through the air and tends to cover the face of the operator so that protection for the eyes is imperative 45 as a guard against blindness. This need is efficiently met by my device. As the disks are held close to the eyes, very narrow slits will furnish ample view of the work and, as the slit extends vertically as well as horizontally, 50 the movements of the gun in all directions

may be observed without fatiguing movements of the head. The slits are not glazed as a film will form on glass and smears so that cleaning of the glass is difficult but while the slits are open they are so narrow that a 55 bead of spray cannot fly through them, and the offset formation turns the spray from the slits so that its tends to collect on the flat face of the disks. Moreover, if a film should form across a slit it may be easily and quickly wiped off with the finger, because of the offset or 60 rib structure. There is always a tendency to drain from the rib, to the outer flat surface and accordingly the paint will not be forced inside the goggles.

65 The disk or guard embodying this invention may be made as a plate for insertion in a pair of goggles, in lieu of the usual glass, or may be included in the goggles during manufacture thereof, it being understood that at no 70 time is the cruciform slit to be closed by glass, wire mesh or any other substance, as such closure would quickly obscure the vision, as paint would collect thereon.

Having thus described my invention, what 75 I claim as new and desire to secure by Letters Patent of the United States is:—

1. An eye guard consisting of an opaque impervious disk having a cruciform offset at its center, a very narrow slit being formed 80 through the offset, longitudinally of all arms thereof.

2. An eye guard consisting of a disk having a cruciform slit therethrough and a rib of cruciform configuration outlining said slit. 85

3. As an article of manufacture, a goggle comprising a frame, disks in said frame, said disks each having a cruciform slit therethrough and a cruciform offset outlining said slit. 90

4. An eye guard comprising a mounting, a disc mounted thereon and adapted to be supported thereby in front of the eye, said disc having a substantially vertical, completely un-obstructed vision slit therethrough and deflecting ribs extending along said slit. 95

In testimony whereof I hereunto affix my signature.

HERBERT C. FOWLER.
